UNITED STATES PATENT OFFICE.

NORMAN H. GAY, OF LOS ANGELES, CALIFORNIA.

ICE-CAN DUMP.

Application filed January 14, 1926. Serial No. 81,355.

The invention relates to new and useful improvements in an ice can dump which may be used for holding the can while it is being filled with the water to be frozen, 5 and which may also be utilized for dumping the ice from the can.

An object of the invention is to provide an ice can dump with means for holding the can in a predetermined inclined position 10 during filling, whereby when said can is filled to overflowing, said can when turned to upright position, will contain a predetermined quantity of water.

A further object of the invention is to 15 provide a device of the above character with means for holding the can both in the inclined position for filling and in an upright position.

A further object of the invention is to 20 provide a device of the above character wherein the can is automatically locked when turned to a predetermined inclined position, and wherein said automatic lock may be readily manually released.

25 These and other objects will in part be obvious and will more particularly hereafter be fully disclosed.

30 In the drawings which show by way of illustration one embodiment of the invention,

Figure 1 is a view partly in side elevation and partly in section showing the improved ice can dump as positioned for the filling of the cans with a predetermined quantity.

35 Fig. 2 is a detail showing a portion of the ice can dump with the parts returned to upright position.

40 Fig. 3 is a detail showing in plan the holding latch and the lugs which cooperate therewith.

45 The invention broadly consists in an ice can dump for holding one or more ice cans, or holding a basket containing one or more ice cans. The ice can dump is pivoted so that it may be swung for emptying the ice from the can, and also swung to upright position. The ice can dump can likewise be swung to an inclined position for filling, and means are provided for holding said ice can dump with the can in a predetermined 50 inclined position so that when said ice can is filled to overflowing while held in this inclined position, it will when turned to upright position contain a predetermined quantity of water.

55 Referring to the drawings, my improved

ice can dump consists of a suitable support 1 having brackets 2 rigidly secured thereto, each of which is provided with an open bearing 3. Mounted on this supporting 60 means is the ice can dump proper which consists of a body portion 4 provided with trunnions 5—5 adapted to be placed in the open sided bearings 3, and thus it is that the ice can dump proper is pivotally supported 65 so that it may be swung on these trunnions and placed either in upright position or inclined position, or in a substantially horizontal or slightly downwardly inclined position for dumping the ice from the can. 70 This body portion 4 of the ice can dump includes a supporting bottom 6, a back member 7 and side members 8. Suitable angle irons are used for strengthening the body portion of the ice can dump. The ice can 75 is indicated at 9 in the drawings. This ice can is of the usual construction and is placed in the ice can dump so as to rest on the bottom portion thereof when in upright position. When inclined the ice can will be supported by the bottom portions and the back portion 7. A single can may be placed in the ice can dump or a series of cans, one 80 beside another, or a basket containing a single can or a series of cans side by side 85 may be placed in said ice can dump. The ice cans are all side by side, however, and symmetrically disposed relative to the pivotal axis of the ice can dump.

Pivotaly mounted on the support 1 is a 90 latch 11; said latch is pivoted at 12 and is provided with a weight 13 which normally tends to turn the latch in a clockwise direction as viewed in Fig. 1. The ice can dump 95 is provided with an angle iron lug 14 which is adapted to engage a notch 15 in the latch. As shown in Fig. 1, the ice can dump is held in a predetermined inclined position by this angle iron lug 14 engaging the notch 15 in said latch 11. 100

Associated with the dump is a filling pipe 16 controlled by a hand valve 17. The ice can is set in this predetermined inclined position and then the water is turned on through the manipulation of the hand valve 17. When the can is filled to overflowing, as indicated in Fig. 1, then the water supply is shut off. The level of the water is indicated at 18 in Fig. 1. It will readily be seen that when the latch is released from engagement with the lug 14 the can may be turned to upright position, and when so turned to upright posi- 110

tion, there will be a predetermined quantity of water therein.

A second angle iron lug 19 is provided which is adapted to engage the notch 15 when the can is in upright position as shown in Fig. 2 of the drawings. The weight 13 normally presses the latch 11 into engagement with the lug 14 or 19 and thus it is that the can dump is automatically locked 10 when the predetermined inclined position is reached, or when the predetermined upright position is reached. This latch can be readily released by the foot of the operator depressing the same. The latch 11 is bent 15 intermediate its ends as clearly shown in Fig. 3, and this provides a clearance space for the lug 14 to swing in so that the latch will cooperate with both lugs.

As shown in Fig. 1 of the drawings, a suitable device 20 may be provided for catching the overflow from the can and directing it to the point where it is desired. Also associated with the ice can dump is an inclined chute 21. When the can is turned to a horizontal position, or slightly inclined beneath the horizontal position then the ice in the can may be discharged therefrom onto the chute 21. The essential feature of the present invention, however, is the means for holding 25 the ice can dump in an inclined position so that the ice can or cans carried thereby may be filled with a predetermined quantity of 30 water.

It will be understood that minor changes 35 in the details of construction may be made without departing from the spirit of the invention as set forth in the appended claims.

What is claimed as new and desired to be 40 secured by Letters Patent is:

1. An ice can support including in combination, a support, brackets mounted on said support, an ice can dump mounted on said brackets so as to swing from a vertical to an inclined position, and cooperating devices 45 carried by said ice can dump and said support for holding said ice can dump and the

can in a predetermined inclined position whereby when the can is filled to overflowing, it will, when turned to upright position, contain a predetermined quantity of water. 50

2. An ice can support including in combination, a support, brackets mounted on said support, an ice can dump mounted on said brackets so as to swing from a vertical to an inclined position, and cooperating devices 55 carried by said ice can dump and said support for holding said ice can dump and the can in a predetermined inclined position whereby when the can is filled to overflowing, it will, when turned to upright position, contain a predetermined quantity of water, said cooperating devices being constructed so as to automatically stop and hold the ice can dump in said predetermined inclined position. 60

3. An ice can support including in combination, a pivoted ice can dump, a lug carried by said ice can dump, a pivoted latch adapted to engage said lug on the ice can dump for holding said ice can dump in a predetermined inclined position, whereby when said ice can is filled to overflowing it will, when returned to upright position, contain a predetermined quantity of water. 65

4. An ice can support including in combination, a pivoted ice can dump, a lug carried by said ice can dump, a pivoted latch adapted to engage said lug on the ice can dump for holding said ice can dump in a predetermined inclined position, whereby when said ice can is filled to overflowing it will, when returned to upright position, contain a predetermined quantity of water, means for automatically swinging said latch into engagement with the lug for stopping and holding the ice can dump when a predetermined inclined position is reached, said latch being manually released from engagement with said lug. 70

In testimony whereof, I affix my signature:

NORMAN H. GAY.
